UNITED STATES PATENT OFFICE.

JOHN M. SCOTT, OF RACINE, WISCONSIN.

RAIL-SPIKE.

No. 911,273.

Specification of Letters Patent.

Patented Feb. 2, 1902.

Application filed July 29, 1901. Serial No. 385,943.

To all whom it may concern:

Be it known that I, JOHN M. SCOTT, a citizen of the United States, residing at Racine, in the county of Racine and State of Wisconsin, have invented certain new and useful improvements in Rail-Spikes, of which the following is a specification, reference being had to the accompanying drawing, forming a part thereof.

10 This invention relates more particularly to spikes for securing railway rails to the wood ties on which they are laid. Its main objects are to obtain a better hold of the spikes on the fibers of the wood, to prevent the spikes from working loose in the ties and being withdrawn therefrom by the jars, vibrations, shocks and strains to which the rails are subjected, and generally to improve the construction and increase the efficiency 20 of spikes of this class without increasing their size, weight or cost.

The invention consists in certain novel features of construction as hereinafter particularly described and pointed out in the 25 claims.

In the accompanying drawing like letters designate the same parts in the several figures.

Figure 1 is a full size side elevation of a 30 railway rail spike embodying the invention; Fig. 2 is a central longitudinal section of the same on the line 2 2, Fig. 3; Fig. 3 is a back elevation of the spike as viewed from above with reference to Figs. 1 and 2; and

35 Fig. 4 is a cross section on the line 4 4, Fig. 2.

The spike is formed with a head *a* of the usual or any suitable shape to engage with the base flange of a rail. It has a chisel point or sharp edge *b* formed at the end 40 opposite the head by the intersection of upwardly and outwardly diverging concave faces *c*. The body of the spike is formed in its back and opposite sides with upwardly and outwardly inclined concave notches *d*

45 recessed into the body of the spike and with transverse crescent shaped shoulders *e* also recessed into the body of the spike extending entirely across the spike in planes approxi-

50 mately perpendicular to its axis. The remaining two sides *f* of the body of the spike have plain parallel faces terminating on each side in sharp or acute angled and approximately straight edges which are formed by the intersection of said plain faces with the curved faces of the notches *d*. The continuous edges or margins along the sides of

the notches *d* serve as flanges to stiffen and strengthen the body of the spike, and forming the notches *d* in its opposite sides admits of correspondingly reducing the amount of metal used in the construction of the spike and consequently reducing its weight, without materially diminishing its rigidity or strength.

In driving the spike into a tie with the chisel point or edge *b* crossing the grain of the wood, the fibers are severed, and their severed ends are bent downward and drawn together by the upwardly and outwardly diverging concave faces of the point and of the notches. As the shoulders *e* pass below and clear them, the ends of the fibers tend to straighten and spread into the deeper lower ends of the notches *d* above said shoulders, against which they act as effective barriers or obstructions preventing the withdrawal of the spike from the tie and reducing any tendency it may have to work loose therein.

I claim:

1. A spike provided with a point and adjacent thereto with an upwardly and outwardly diverging concave face recessed in the body of the spike and adapted to compress wood fibers laterally, said spike being provided with a notch also recessed in the body of the spike whereby a shoulder is formed beyond said concave face against which the fibers which have been compressed laterally by said concave face are adapted to rest.

2. A rail spike of general quadrangular cross section, two opposite faces of said spike each being provided with a series of downwardly and inwardly inclined concave notches and transverse crescent-shaped shoulders with inwardly curved edges extending entirely across the spike at the lower ends of the notches, the lowermost notches of each series intersecting to form the point of the spike.

3. A rail spike of general quadrangular cross section, two opposite faces of said spike each being provided with a series of downwardly and inwardly inclined concave notches and transverse crescent-shaped shoulders with inwardly curved edges extending entirely across the spike at the lower ends of the notches and said notches extending entirely across the spike throughout their length, whereby the sides of the notches at the corners of the spike maintain substantially uniform straight lines, the lowermost

notches of each series intersecting to form a chisel point for the spike.

4. A rail spike of general quadrangular cross section, two opposite faces of said spike each being provided with a series of downwardly and inwardly inclined concave notches and transverse crescent-shaped shoulders with inwardly curved edges extending entirely across the spike at the lower ends 10 of the notches and said notches extending entirely across the spike throughout their length, whereby the sides of the notches at the corners of the spike maintain substantially uniform straight lines, the lowermost 15 notches of each series intersecting to form a chisel point for the spike, the other two sides of the spike having plain faces which merge with the concave faces of the notches to form continuous and approximately straight sharp edges.

5. A spike provided with a point and adjacent thereto with an upwardly and outwardly diverging concave face recessed in the body of the spike and adapted to compress

wood fibers laterally, said spike being also 25 provided with a second upwardly and outwardly diverging concave face recessed in the body of the spike and adapted to compress wood fibers laterally, said second concave face being recessed adjacent said first 30 mentioned concave face, to form a shoulder above said first mentioned concave face, and said spike being further provided with a notch recessed in the body of the spike above said second mentioned concave face, to form 35 a shoulder above said second concave face against which the fibers which have been compressed laterally by said concave faces are adapted to rest, said concave faces and said notch extending across the entire side 40 of the spike in which they are recessed.

In witness whereof I hereto affix my signature in presence of two witnesses.

JOHN M. SCOTT.
